United States Patent Office

Des. 177,752
Patented May 22, 1956

177,752

PLAY GYM STRUCTURE

Edwin L. Parker, Wadsworth, Ohio, assignor to Blazon,
Inc., Akron, Ohio, a corporation of Ohio

Application November 2, 1955, Serial No. 38,699

Term of patent 14 years

(Cl. D34—5)

FIG. 1

FIG. 3

FIG. 2

Fig. 1 is a perspective view of the play gym structure,
Fig. 2 is an end elevation taken from the left side of
Fig. 1, and

Fig. 3 is an end elevation taken from the right side
of Fig. 1.

I claim:

The ornamental design for a play gym structure, sub-
stantially as shown.
